UNITED STATES PATENT OFFICE.

ROBERT FISCHER, OF BROOKLYN, NEW YORK.

SAFETY WATCH-GUARD.

1,074,543.

Specification of Letters Patent. Patented Sept. 30, 1913.

Application filed June 23, 1912. Serial No. 706,016.

To all whom it may concern:

Be it known that I, ROBERT FISCHER, a citizen of the United States, residing at Brooklyn, in the county of Kings and State 5 of New York, have invented new and useful Improvements in Safety Watch-Guards, of which the following is a specification.

This invention relates to safety watch guards and has for its object to provide a 10 simple and inexpensive device of this character that may be fastened within the pocket for protecting the watch against theft.

A still further object is to provide a device of this character that is adapted for 15 quick and reliable adjustment to the pocket and one in which the watch may not be disconnected therefrom whenever it is necessary to withdraw the same to determine the time.

20 To these ends the invention consists in the novel details of construction and combination of parts more fully hereinafter described and particularly pointed out in the claim.

25 Referring to the accompanying drawings forming a part of this specification in which like numerals designate like parts in all the views:—Figure 1 is a side elevational view of my improved device showing a watch connected thereto, the parts in the position 30 they would assume when within a pocket. Fig. 2 is a detail view of the device showing the chain partly withdrawn, with parts also shown broken away for the sake of 35 clearness, and Fig. 3 is an enlarged detail broken sectional view of the device.

My improved watch guard consists of a 40 flexible tubular element 1 provided with the covering 2 and closed at its ends by the binding end pieces 3 and 4, the end piece 4 having connected thereto a spring actuated clip 5 which is adapted to be connected over the edge of the pocket for securely locking the watch guard in position.

45 Held within the tubular element 1 is a chain or other connection 6 provided at its outer end with a ring 7 and at its inner

end with an enlarged head 8. A spring 9 bearing at one end on the enlarged head 8 and at the other end against the inner end 50 of the end piece 4, yieldingly holds the chain 6 within the tubular element 1. The chain operates within the aperture 10 in the end piece 4 as clearly shown in Fig 3. Connected to the ring 7 is the usual swivel 55 watch connection 11 to which is connected through the ring 12, the watch 13.

When in use my improved device is placed within the pocket; the spring actuated clip engaging the edge thereof and securely holding the device in position. When the watch is withdrawn, the chain 6 through the swivel connection 10, will also be yieldingly withdrawn, the limit of this movement being dependent upon the length of chain used. 65 When the watch is inserted in the pocket the chain 6 will through the action of the spring 9, also be returned to its normal position.

It is obvious that those skilled in the art 70 may vary the details of construction and arrangements of parts without departing from the spirit of my invention and therefore I do not wish to be limited to such features except as may be required by the claim. 75

What is claimed as new is;

In a watch guard, the combination with 80 a clasp; of a flexible tube, caps at the ends of the tube, one of which caps is provided with an opening and is secured to the said clasp, a chain within the tube and passing through the opening in the cap, the projecting end of the chain being provided with a swivel, a spring located in the tube and wound around the chain and adapted to 85 return the chain to within the tube when the said chain is withdrawn, substantially as described.

In testimony whereof I affix my signature in presence of two witnesses.

ROBERT FISCHER.
